UNITED STATES PATENT OFFICE.

JOEL TIFFANY, OF HINSDALE, ILLINOIS.

SEAT-PAD FOR WATER-CLOSETS.

SPECIFICATION forming part of Letters Patent No. 443,170, dated December 23, 1890.

Application filed April 5, 1890. Serial No. 346,738. (No model.)

To all whom it may concern:

Be it known that I, JOEL TIFFANY, a citizen of the United States, residing at Hinsdale, in the county of Du Page and State of Illinois, have invented certain new and useful Improvements in Seat-Pads for Water-Closets, Privies, and Commodes, of which the following is a specification.

The object of this invention is to provide an absolutely fresh seat-surface for each use of a water-closet, privy, or commode, whereby cleanliness and freedom from contagion are secured.

The invention consists, essentially, in an annular pad adapted for a water-closet seat, privy-seat, or commode-seat, composed of a series of superposed separable sheets of suitable material.

Figure 1 of the accompanying drawings represents a perspective view of a water-closet provided with this improved seat-pad. Fig. 2 represents a plan view thereof. Fig. 3 represents a vertical transverse section of a portion of a water-closet having a hinged seat provided with this improved seat-pad in raised position. Fig. 4 represents a similar section, the seat-pad being in position for use. Fig. 5 represents a transverse section on an enlarged scale of this improved seat-pad on line 5 5 of Fig. 2. Fig. 6 represents an enlarged transverse section through a portion of this improved seat-pad on line 6 6 of Fig. 2, the top layer of the pad being illustrated as in the process of removal.

Similar numerals of reference indicate corresponding parts in the different figures.

The water-closet bowl 10, the seat 20, and the back 30 may be of any suitable construction. In the drawings the seat 20 is represented as hinged to the back by means of hinges 21.

An annular seat-pad 40, composed of a number of superposed annular sheets 41, is adapted to fit the seat and constitutes the seat-surface thereof. The layers composing this pad are united in such a manner as to be easily separable one from another. Mucilage or other suitable cement may be applied to their edges at several points for the purpose of attaching the sheets together, or they may be subjected to pressure and molded so as to cause them to adhere sufficiently for the pur-

pose. The pad is provided with a notch 42 to facilitate the removal of the top sheet, the edges of the sheets at the notch being free 55 from cement.

The sheets 41 comprising the pad are preferably composed of water-proof material to prevent moisture from penetrating the underlying sheets and to keep them in condition 60 for use for surface sheets. These sheets may be composed of paper made water-proof by any process of waterproofing paper known to those skilled in the art. The pad may also be medicated, if desired, for sanitary purposes. 65

The pad proper is preferably mounted upon a base-plate 43, which may be hinged to the seat 20, and a spring 50 is attached at one end to the pad and at the other end to the water-closet back to automatically raise the seat-pad from the seat when not in use. The base-plate 43 may be provided with a spring-catch 44 for holding down the pad. 70

This improved pad may be applied to privy-seats, commode-seats, and the seats of invalid-chairs, as well as to water-closet seats. It may be manufactured in different sizes and shapes to fit various sizes and shapes of such seats and placed on the market as an independent article of manufacture in condition 75 to be applied to the seat by the user.

In the use of this pad the top sheet or layer thereof is removed after each use of the seat or as often as may be required to present a 80 clean surface. The detachment of the top layer may be effected by placing the finger in notch 42 and lifting said layer between the thumb and finger. When the pad is exhausted, a new pad may be put in its place. 85

The term "annular" as applied to the pad herein described and claimed or its component sheets is to be understood as including a pad having an opening adapted for a water-closet or privy seat whether the outer margin 90 of said pad be circular, oval, or otherwise.

I claim as my invention—

1. A seat-pad for a water-closet, privy, or commode, consisting of a number of annular superposed separable sheets.

2. A seat-pad for a water-closet, privy, or commode, consisting of a base-plate and a pad mounted thereon composed of a number of superposed separable sheets. 100

3. The combination of a seat for a water-closet, privy, or commode and a seat-pad thereon composed of a number of superposed separable sheets.
- 5 4. The combination of a seat for a water-closet, privy, or commode, an annular plate hinged thereto, and an annular pad mounted on said plate, said pad being composed of a number of superposed separable sheets.
- 10 5. The combination of a seat for a water-closet, privy, or commode, an annular plate hinged thereto, an annular pad mounted on said plate, said pad being composed of a num-
- ber of superposed separable sheets, and a spring for swinging said plate out of position 15 when not in use.
6. A seat-pad for a water-closet, privy, or commode, composed of a number of annular superposed separable sheets, said pad being provided with a notch to facilitate the re- 20 removal of the successive top sheets.

JOEL TIFFANY.
